RAILWAY SIGNALING SYSTEM

George D. Hanchett, Jr., Millburn, N. J., assignor
to Radio Corporation of America, a corporation
of Delaware

Application October 25, 1947, Serial No. 782,087

4 Claims. (Cl. 246—34)

1

This invention relates to railway signaling systems and has for its principal object the provision of an improved railway signaling system and method of operation which permit the operation of trains at higher speeds and over longer blocks of track than has been practical heretofore.

In the past, railway signals have been controlled by relays which are responsive to track voltages. That is, a track has a voltage applied to one end of a block. A relay is connected to the other end of the block. The presence of a train on the track shunts the voltage and decreases the current flowing through the relay. This decrease in current deenergizes the relay and produces operation of the switch by which the signal light or its equivalent is controlled.

With the ever increasing train speeds of today, blocks using the relay shunt method are no longer altogether satisfactory for the reason that greater block lengths are required to accommodate the higher train speeds and the resulting shunting effect of the ties makes the sensitivity of the signaling system too low for satisfactory operation.

Important objects of the present invention are to provide a railway signaling system which is more sensitive to the presence of a train on the protected blocks of track, and to provide a railway signaling system which is of simple construction is inexpensive and operates without undue noise, thus making it suitable for use in connection with model or toy train operation.

The invention will be better understood from the following description considered in connection with the accompanying drawings and its scope is indicated by the appended claims.

Referring to the drawings:

Figure 1 is a wiring diagram of an embodiment of the invention wherein the train and the signaling system are operated from the same source of alternating current.

Figure 2 is a modification wherein the train is operated from a direct current source and the signaling system is operated from an alternating current source, and

Figure 3 is a wiring diagram of a grade crossing signal circuit which may be utilized in connection with the signaling systems of Figures 1 and 2.

The signaling system of Figure 1 includes three gaseous conduction tubes V_1 , V_2 and V_3 which have operating potential applied to their anodes from input leads 10 and 11 through a switch 12, thence through a fuse 13 and a resistor R_1 . The

2

cathode of the tube V_1 is connected to the grounded terminal indicated by conventional symbol through a green lamp 14 and a part of the secondary winding 16 of a transformer T which has its primary winding excited from the leads 10 and 11, thus injecting into the output circuit of the tube V_1 a voltage (being the difference between the 16.3 volt tap and the 6.3 volt tap) of nominally 10 volts which is opposed to that applied from the leads 10 and 11.

From the 30 v. lead of the secondary winding 16, signal potential is applied to the control grid 15 of the tube V_1 . This potential is sufficiently positive to cause conduction of the tube V_1 when the rails 1 and 2 are not interconnected through a train. The voltage applied between grid 15 and the cathode of V_1 may be taken positive because of the transformer T connections. When the voltage is taken as more negative, no current, of course, flows in the tube. All the grids and anodes of tubes V_1 , V_2 , and V_3 swing positively with respect to their respective cathodes, at the same time on the same half cycle; as may be verified by their connections to the transformer T. Therefore, since these tubes can conduct only during this half cycle, for convenience in description, the positive-going voltages with respect to cathodes are termed simply positive, in describing Fig. 1. On the other negative half cycles, none of the tubes conduct. The applied voltage is of a high enough frequency so that, with the persistence of vision, if the lamps 14, 19, 21 are lighted on half cycles, they will appear to be lighted continuously.

Potential is applied to the screen grids of the tubes V_1 , V_2 and V_3 from the different taps of a resistor R_2 which is connected across the lower part of the secondary winding 16.

When a train approaches in the direction indicated by an arrow, a circuit is completed from the 30 v. lead through a connection 17, the rail 2, the train rail 1 and a resistor R_4 back to the 6.3 v. lead of the winding 16. Since the resistor R_4 is connected between the cathode and control grid 18 of the tube V_3 , a potential which may be taken as more positive, is applied between the grid 18 and the cathode of V_3 , and the tube V_3 begins to conduct current through the resistor R_1 , also resistor R_3 , thus lighting a red lamp 19 by the voltage across resistor R_3 , which is connected between the cathode of the tube V_3 and the low voltage 6.3 v. lead of the winding 16.

At the same time, the green light 14 is extinguished due to the fact that the anode-to-cathode voltage of the tube V_1 is now reduced to the

3

ionization drop across the tube V_3 plus voltage across R_8 plus the opposed potential derived from the 16.3 v. and 6.3 v. taps of the secondary winding 16, this reduced voltage being too low to produce conduction in the tube V_1 .

When the train goes onto the second block B of the track the connection of rail No. 2 to the resistor R_4 is broken and the lower terminal of a resistor R_3 is connected to the rail 2. But this lower terminal of resistor R_3 is also connected to the control grid 20 of tube V_2 through resistor R_6 . Therefore the voltage from the transformer 30 v. terminal is applied to control grid 20. The cathode of V_2 is connected through resistor R_5 to the 11.3 v. tap of transformer T_1 . Hence under these conditions when the train is in block B, a potential is applied to control grid 20 more positive than that on the cathode of tube V_2 by about (30-11.3) volts or about 18.7 volts, when the 30 v. tap is positive with respect to the 11.3 volt tap. Under these conditions, the tube V_2 draws current through the resistor R_1 and a yellow lamp 21 which is connected between the cathode of the tube V_2 and the low voltage tap 11.3 v. of the winding 16 is lighted.

At the same time, the red lamp 19 is extinguished due to the loss of voltage on the resistor R_4 and interruption of the current of the tube V_3 . The tube V_1 remains extinguished for the reason that its cathode-to-anode voltage is now the ionization voltage of the tube V_2 plus voltage across R_6 plus the opposed voltage derived from the 16.3 v. and 6.3 v. taps of the secondary 16.

The resistors R_5 , R_6 and R_7 are grid leak resistors. The resistors R_8 and R_9 are equalizing resistors which function to cause the lamps 14, 19 and 21 to be lighted to the same brightness. Since the tube V_2 has more voltage than the tube V_1 and the tube V_3 has more voltage than the tube V_2 or the tube V_1 , the red light would be brightest and the green light would be dimmest in the absence of the resistors R_8 and R_9 . By the use of these resistors, equal light intensity of all three lamps is obtained.

When it is desired to operate the signal system from a two rail system, a special control signal must be provided. This signal must be so separated from the power drive voltage that the tubes V_1 , V_2 and V_3 will be controlled only by the signal voltage. In the modification of Figure 2, this is accomplished by using unidirectional voltage for motive power and pulse voltage for signaling purposes.

In this modification, a gaseous conduction tube V_4 has potential applied to its anode from the input lead 10 through the primary winding 21 of a transformer T_1 , and a capacitor C_2 which is shunted by a resistor R_{10} . The cathode of the tube V_4 is connected to a tap of the secondary winding of transformer T at a point where the voltage is less than the filament voltage. The control grid 22 of the tube V_4 is connected to its cathode through a phase shifting circuit including resistors R_{11} and R_{12} and a capacitor C_1 . The grid to cathode circuit may be traced as follows: resistor R_{12} and capacitor C_1 are connected in series across the heater of tube V_4 ; resistor R_{11} is connected between their junction and the grid 22; the heater terminals are connected to the lowest (as viewed in Fig. 2) tap and the 6.3 v. tap of transformer T ; the center tap (3.15 v.) between these two transformer taps is connected directly to the cathode. The secondary winding 23 of the transformer T_1 has one of its leads

5

coupled to the rail 2 through a capacitor C_3 and has its other terminal connected to the junction between the secondary windings 24 and 25 of transformers T_3 and T_2 . The primary windings 26 and 27 of the transformers T_3 and T_2 are connected respectively between the cathode and control grid 28 of the tube V_3 and between the cathode and control grid 29 of the tube V_2 . Power to the preceding block (not shown) may be obtained through winding 23 at the junction point of the secondaries 24 and 25. It, therefore, will obtain its unidirectional current for propulsion as well as pulse current for signal operation.

When no train is on block A or B, the green lamp 14 is lighted in the current pulses from manner previously explained, the circuit of the tube V_4 does not induce voltages in the secondaries 26 and 27 of transformers T_3 and T_2 . Therefore, the green lamp stays lighted, because there is no current in the primaries 24 and 25, to actuate their secondaries to cause either of tubes V_2 and V_3 to start conduction, and tube V_1 continues to conduct, keeping on green light 14.

The entrance of a train into block A completes 25 a circuit whereby signal pulse current and propulsion current is drawn through secondary 24. Signal transient pulses are generated continuously by tube V_4 and are so phased that the anodes of V_1 — V_2 and V_3 are positive when these pulses occur. The sharp pulses are produced by the charge current of capacitor C_2 through transformer T_1 . Capacitor C_3 is used as a bypass to lower the return circuit impedance for these pulses thus the pulse current is first passed 35 through secondary 24, the train, capacitor C_3 and back to winding 23. The pulse current passing through winding 24 produces a pulse voltage across winding 26 ionizing tube V_3 thus operating lamp 19 of the signal.

When the train moves onto block B, conduction of the tube V_2 is started in the same way by the pulse signal voltage applied through the transformer T_2 to the grid 29. As a result, the yellow lamp is lit and the red lamp is extinguished by the loss of voltage on the grid 28 of the tube V_3 .

The purpose of the transformers T_3 and T_2 is to 45 separate the unidirectional motive power voltage from the pulse signal voltage. The impedance of the transformers T_2 and T_3 is made so low that the signal voltage is not affected by the charging potentials of the motive power voltage.

In either system, when the train is in two blocks, for example blocks A and B, at the same time, only one of tubes V_1 , V_2 , V_3 can be conductive. The reason is that when one of them is conducting, the voltage drop across resistor R_1 reduces the anode voltage available at the anode of any other tube to a value below that required to allow the other tube to be fired. It is well understood that gas tubes require a higher anode igniting voltage than that required to maintain conduction. Since only one of tubes V_2 , V_3 can be conductive at the same time, only one of the yellow or red lights may be on at the same time.

It is to be noted that when the voltages go negative neither V_1 , V_2 nor V_3 will conduct, when the voltages go positive, however, the voltage across V_3 will be the first to reach firing potential because of their comparative peak magnitudes, therefore the red light will remain lighted until the train occupies block B exclusively.

The grade crossing signal circuit of Figure 3 75 may be utilized in connection with the signaling

systems of Figures 1 and 2 by connecting its lead 30 to the high voltage side of the resistor R₄ of Figure 1 or the secondary winding 26 of Figure 2.

This grade crossing signal circuit includes a controlled grid rectifier including the tube V₇ and a low frequency inverter including the tubes V₅ and V₆. The tube V₇ is operated as a positive grid gaseous conduction tube by returning the shield grid 31 to a tap 32 on a resistor R₁₃, the voltage of this tap 32 being negative when the voltage of the anode 33 is positive. As a result, the tube V₇ conducts current only when a positive voltage is applied through the lead 30 to the control grid 34. When the grid 34 has a positive potential applied to it through the lead 30, the tube V₇ functions to charge a capacitor C₄ from the positive side of which voltage is applied through a lead 35 to the midpoint of the anode resistor R₂₁ of the inverter. The negative terminal of the capacitor C₄ is connected through a lead 36 to the common terminal of lamps 38 and 39. The individual terminals of the lamps 38 and 39 are connected respectively to the cathodes of the tubes V₆ and V₅.

As is usual in this type of inverter, (1) the resistor R₂₁ is shunted by a capacitor C₇, (2) the anode of the tube V₆ is coupled to the grid of the tube V₅ through a circuit including a capacitor C₅ and resistor R₁₈ and (3) the anode of the tube V₅ is coupled to the grid of the tube V₆ through a circuit including a capacitor C₆ and resistor R₉.

With these connections, the unidirectional voltage of the capacitor C₄ is converted to a low frequency alternating voltage by the inverter and the lamps 38 and 39 are lighted alternately so long as a positive voltage is applied through the lead 30.

Obviously, the warning lights 19, 21, and 14 should be placed at the entrance to block A as shown in Figs. 1 and 2, and the grade crossing lights 38 and 39 should be placed at the appropriate grade crossing which is preferably somewhere intermediate and near the center of blocks A and B, also as shown in Figs. 1 and 2.

Thus, the invention provides an improved railway signaling system which is highly sensitive to the presence of a train, may be used in connection with either alternating or direct current motive power, and is readily combined with a grade crossing signal circuit.

What I claim is:

1. In combination, a transformer having a primary winding and a secondary winding, a plurality of signal elements, a corresponding number of gaseous conduction devices each having a cathode, an anode and a control electrode, the anodes of said devices being connected through a common impedance to one terminal of said primary winding, a point of common reference potential, the other end of said primary winding being connected to said point of common reference potential, a first tap on said secondary winding adjacent one end thereof connected to said point of common reference potential, the cathode of one of said devices being connected

60
65

in series with its corresponding signal element to a second tap on said secondary winding intermediate the ends thereof, each cathode of the other of said devices being connected in series with a separate impedance to an individual tap on said secondary intermediate said second tap and said point of common reference potential, each of the other of said signal elements being connected in parallel with the separate impedance element associated with its corresponding gaseous conduction device, a connection from a tap on said secondary winding adjacent the other end thereof to the control electrode of said one device, the windings of said transformer being so poled and the voltages across said taps being so related that said one device is normally conducting and each of the other of said devices is normally non-conducting, and means for successively applying to each control electrode of the other of said devices a potential thereby causing each of said other devices to be successively made conducting and each other of said devices is rendered non-conducting, by reason of the lowered anode to cathode potential resulting from ionization of the conducting tube.

2. The combination as set forth in claim 1 in which said means for successively applying control pulses comprises impedance elements each arranged to be connected to a different block of a railway track through said secondary winding and means for applying a voltage drop across said impedance elements each to the control grid of a different one of said other devices.

3. The combination as set forth in claim 1 in which said means for successively applying control pulses comprises transformers each having its secondary winding connected in the control grid circuit of a different one of said other devices and each having its primary winding connected to a different successive block of a railway track, and means responsive to the presence of a train on said successive blocks for successively energizing said other devices and de-energizing said one device.

4. The combination as set forth in claim 1 in which said means for successively applying control pulses comprises transformers each having its secondary winding connected in the control grid of a different one of said other devices and each having its primary winding connected to a different successive block of a railway track, and means including a gaseous conduction device connected to apply a pulse voltage to each of the said primary windings of said transformers in response to the entrance of a train into each successive block.
